J. H. PAYNE, JR.
METHOD OF AND MEANS FOR PRODUCING ALTERNATING CURRENTS.
APPLICATION FILED SEPT. 14, 1916.
1,400,235. Patented Dec. 13, 1921

Inventor:
John H. Payne, Jr.
by Albert G. Davis
His Attorney.

UNITED STATES PATENT OFFICE.

JOHN H. PAYNE, JR., OF SCHENECTADY, NEW YORK, ASSIGNOR TO GENERAL ELECTRIC COMPANY, A CORPORATION OF NEW YORK.

METHOD OF AND MEANS FOR PRODUCING ALTERNATING CURRENTS.

1,400,235.

Specification of Letters Patent.

Patented Dec. 13, 1921.

Application filed September 14, 1916. Serial No. 120,070.

To all whom it may concern:

Be it known that I, JOHN H. PAYNE, Jr., a citizen of the United States, residing at Schenectady, in the county of Schenectady, 5 State of New York, have invented certain new and useful Improvements in Methods of and Means for Producing Alternating Currents, of which the following is a specification.

10. My present invention relates to the production of continuous alternating currents by the use of electron discharge devices comprising a cathode capable of emitting electrons, an anode, and a discharge controlling member or grid, all inclosed in a highly evacuated receptacle.

The object of my invention is to produce radio frequency oscillations by means of such a device and to break up these oscillations into groups having a definite or audible frequency. A further object of my invention is to simultaneously produce by means of a single device oscillations of a plurality of frequencies.

25. The features of my invention which I consider novel are pointed out with particularity in the appended claims. The invention itself, however, both as to its organization and method of operation will best be understood by reference to the following description taken in connection with the accompanying drawing in which I have illustrated one of the circuit arrangements whereby my invention may be carried into effect.

30. As indicated in the drawing an electron discharge device 1, comprises a cathode 2, supplied by current from the battery 3 for heating to incandescence, an anode 4 and a discharge controlling member or grid 5 inclosed in an evacuated receptacle 6. An external circuit between cathode 2 and anode 4 comprises a source of direct current 7 and inductances 8 and 9. This circuit for convenience of description I designate the plate circuit. A second circuit between the cathode and grid 5 includes inductances 10 and 11. This circuit for convenience of description I designate the grid circuit.

35. It is well known that in an organization of this kind if the grid and plate circuits are properly coupled together continuous alternating currents may be produced. I

designate such an arrangement a "self excited electron discharge device"; that is, one capable of producing alternating currents of itself in contra distinction to the usual arrangement in which alternating currents are produced only when an alternating exciting current is supplied from another source. In the present case the coupling between the grid and the plate circuits is provided by condensers 12, 13 and 14. The inductances 9 and 11 and the capacities 12 and 13 are preferably so chosen that radio frequency oscillations will be set up in the circuit which includes these inductances and capacities. The frequency of these oscillations may be varied by varying the capacity of condenser 12, which is preferably of smaller capacity than condenser 13. Inductances 8 and 10 and condensers 13 and 14 are so proportioned that the circuit including these inductances and capacities will be resonant to a different and preferably an audible frequency and the frequency of the alternating currents generated in this circuit may be varied by varying the capacity of condenser 14. Because of the complexity of the current and voltage conditions in the circuits which are organized in this way it is difficult to state precisely the manner in which it operates. I have found, however, that by coupling an antenna 15 to the inductance 9 by means of the coil 16 high frequency oscillations will be produced in the antenna 15 and these high frequency oscillations will be broken up into groups having a frequency equal to the frequency of the currents produced in the circuit 8, 90 13, 10, 14. It is also possible by varying the tuning of the two resonant circuits to produce oscillations in the two circuits which differ from each other in frequency by a small amount either at audible or radio frequencies, and by means of the currents thus produced impress upon the antenna a composite wave which is a combination of the two frequencies in any desired manner.

40. While I have illustrated a single form of my invention, it is by no means limited to the particular form of electron discharge devices illustrated or to the exact circuit connections shown, as many modifications therein may be made without departing 105 from the scope of the appended claims.

For example, more than two resonant circuits may be utilized and oscillations of as many frequencies as desired may simultaneously be produced by a single electron discharge device. By coupling the utilization circuits to the different resonant circuits oscillations of any one of the different frequencies may be employed for any desired purpose. Some of these oscillations 10 may be of radio frequency, some of audio frequency, or all may be of audio frequency, or all may be of radio frequency.

What I claim as new and desire to secure by Letters Patent of the United States, is:—

15 1. The method of operating a radiating system comprising a self-excited electron discharge device which consists in causing said device to produce two separate currents, one of radio frequency and one of 20 audio frequency, causing the two currents to interact to produce radio frequency currents having an audible group frequency equal to that of the audio frequency currents produced and utilizing the currents thus produced for effecting a useful radiation of energy.

2. Means for producing radio frequency currents having a definite group frequency comprising an electron discharge device having plate and grid circuits, two circuits which include separate inductances in both grid and plate circuits and which are resonant to two different frequencies associated therewith in such a way that alternating 35 currents will be produced in said resonant circuits, an electrostatic coupling between said resonant circuits, and a utilization circuit operatively related to said plate circuit.

3. Means for producing radio frequency 40 currents having an audible group frequency comprising a self-excited electron discharge device having plate and grid circuits, two circuits directly associated with both plate and grid circuits in such a way that alternating currents will be produced therein, one of said circuits being resonant to a radio 45 frequency and the other to an audible frequency equal to the group frequency desired, and a utilization circuit operatively related 50 to said plate circuit.

4. Means for producing radio frequency currents having an audible group frequency comprising an electron discharge device having an anode, a cathode and a grid inclosed in 55 an evacuated receptacle, a circuit connecting the cathode and anode which includes a direct current source of energy, a second circuit connecting the cathode and grid, a plurality of condensers coupling the two circuits in such a way as to form therewith two coupled circuits which are resonant to two 60 different frequencies.

5. Means for producing radio frequency currents having an audible group frequency 65 comprising an electron discharge device hav-

ing an anode, a cathode and a grid inclosed in an evacuated receptacle, a circuit connecting the cathode and anode which includes a source of energy and a plurality of inductances, a circuit connecting the cathode and 70 grid which also includes a plurality of inductances and a plurality of condensers connected in multiple between the two circuits, said inductances and condensers being so proportioned and arranged as to form two 75 coupled circuits, one of which is resonant to audible frequencies and the other of which is resonant to radio frequencies.

6. The combination with an electron discharge device comprising an anode, a cathode and a grid inclosed in an evacuated receptacle of a resonant circuit associated with the device in such a way that radio frequency currents will be produced in said circuit, a second circuit resonant to audio frequencies 85 and associated with the first circuit in such a way that the radio frequency currents in the first circuit will be broken up into groups of audible frequency corresponding to the frequency of the second circuit, and a utilization 90 circuit operatively related to said first circuit and adapted to receive energy therefrom.

7. Means for producing alternating currents of a plurality of frequencies comprising 95 a self-excited electron discharge device, a single plate circuit and a single grid circuit for said device, a plurality of circuits which are resonant to the different frequencies desired directly associated with said plate circuit and said grid circuit in such a way that alternating currents will be produced in said resonant circuits, and a utilization circuit operatively related to said plate circuit.

8. Means for producing a plurality of alternating currents of different frequencies comprising a self-excited electron discharge device, a single plate circuit and a single grid circuit for said device, a plurality of circuits which are resonant to the different 100 frequencies desired, directly associated with both plate and grid circuits in such a way that alternating currents will be produced in said resonant circuits, and means whereby the currents thus produced may be caused to 105 interact one upon another.

9. Means for producing alternating currents of a plurality of different frequencies comprising an electron discharge device, a plate circuit for said device, a grid circuit 110 for said device, and a plurality of resonant circuits each of which is formed in part by a portion of the grid circuit and in part by a portion of the plate circuit, and so associated with those circuits that alternating 115 currents of different frequencies will be produced in said resonant circuits.

10. The method of operating a radiating system having a self-excited electron discharge device with plate and grid circuits 120

associated therewith, which consists in caus-
ing said device to generate two separate cur-
rents, one of radio frequency and one of
audio frequency, causing the two currents to
5 interact to produce in the plate circuit radio
frequency currents having an audible group
frequency equal to the frequency of the au-
dio frequency current generated and im-
pressing the current thus produced upon the
radiating system.

In witness whereof, I have hereunto set
my hand this 12th day of September, 1916.

10

JOHN H. PAYNE, JR.
